PLATFORM TOY

Walter C. Bolling, 332 Forest Ave.,
Palo Alto, Calif. 94301

Filed Feb. 12, 1973, Ser. No. 331,504

Term of patent 14 years

Int. Cl. D21—01

U.S. Cl. D34—15 AJ

FIG. 1

FIG. 2

FIG. 3

FIG. 1 is a perspective view of a platform toy showing my new design;

FIG. 2 is a top plan view thereof shown at reduced scale; and,

FIG. 3 is a front elevational view thereof.

The shading in FIGS. 1 and 2 indicates contrasting surface ornamentation.

I claim:

The ornamental design for a platform toy, as shown and described.
